UNITED STATES PATENT OFFICE.

WILLIAM KEMP, OF ST. LOUIS, MISSOURI.

VALVE LEVER.

Application filed February 1, 1926. Serial No. 85,091.

My invention relates to valve levers, and more particularly to turning chronometer valve levers, although not necessarily limited thereto as it is applicable to other types of valves, and, it is a distinct and practical improvement to overcome certain practical objections to, and defects in the ordinary single piece levers heretofore used in connection with chronometer valves.

10 The object of my present invention is the provision of an adjustable lever consisting of a plurality of lever elements for opening and closing chronometer valves by means of any well known controlling mechanism, 15 such as a damper regulator control mechanism, or a float control mechanism.

A further object of the invention is to provide a longitudinally and transversely adjustable lever for turning chronometer 20 valves to increase or decrease the maximum, or to increase or decrease the minimum capacity of the valve, each being independent of one another, or both can be adjusted at the same time.

25 A further object of the invention is to provide a valve lever which possesses advantages in points of simplicity and efficiency, and, at the same time proves itself comparatively inexpensive in manufacture.

30 With the above and other objects in view, the invention consists in the novel features of construction, arrangement and combination of parts hereinafter more fully described and finally pointed out in the claims 35 hereto appended.

Referring to the accompanying drawings forming a part of this specification wherein like characters of reference denote similar parts throughout the several views:

40 Fig. 1, is a front elevation of a valve lever applied to a chronometer valve embodying the features of my invention.

Fig. 2, is a top plan view thereof.

45 Fig. 3, is a detail in side elevation of the clevis like element adjusted to a position with its longitudinal axis at an angle to the longitudinal axis of the outer lever member.

50 Referring to the drawings, the reference character 1 represents the casing of a turning chronometer valve having the valve stem 2.

In carrying out the aim of my invention, I provide the valve casing 1 with a suitable face plate 3 which is fixed thereto in any 55 suitable manner, such for instance as by set screws 4.

The face plate 3 is preferably provided with two openings designated 5 and two openings designated 6, so that either set of openings can receive the fastening devices 4 for securing the face plate 3 to the valve casing 1.

When the fastening devices are received in the openings 5 of the face plate 3, the longitudinal axis of the face plate will lie at a right angle to the longitudinal axis of the valve casing 1, and when the fastening devices are received in the openings 6 of the face plate 3, the longitudinal axis of the face plate will lie parallel with the longitudinal axis of the valve casing 1, as is manifest. When the valve casing 1 is applied to vertically disposed pipes, the fastening devices pass through openings 5 in the face plate 3, and when the valve casing 1 is applied to horizontally disposed pipes, the fastening devices 4 pass through openings 6 in the face plate. The face plate 3 is provided at one end with a suitable bearing boss 7 and is also provided intermediate its ends with a pair of opposed ears 8 for receiving suitable stop screws 9, which screws limit the turning movement of the valve stem 2 in either direction.

A suitable outer lever member 10 having a longitudinal slotted opening 11 intermediate its ends, is pivotally connected at its inner end, as at 12 to the bearing boss 7 of the face plate 3.

An inner lever member 13 having the split head 14 is clamped to the valve stem 2 by means of a suitable fastening device 15 which fastening device is positioned near the inner end of the split head 14, as clearly shown in Fig. 1. The valve stem 2 is also provided with an inner nut 16 and an outer nut 17 which also serve to prevent displacement of the lever member 13 upon the valve stem 2. The end of inner lever member 13 opposite the split head 14 thereof is provided with a longitudinally disposed slotted opening 18.

A suitable intermediate clevis lever member 19 having a transversely disposed arc shaped slotted opening 20 and a longitudinally disposed slotted opening 21 is clamped to the outer lever member 10 in any desired adjusted position with relation thereto by means of a suitable fastening device 22 which passes through the slotted opening 11 of the outer lever member 10 and the curved slotted opening 20 of the

clevis lever member 19. The outer lever member 10 is also provided with a suitable guide and pivot pin 23 which passes through the slotted opening 21 of the clevis lever member 19 and acts as a fulcrum point, or pivot pin to permit turning movement of the clevis lever member 19 when desired, by merely loosening the fastening device 22.

The inner end of the clevis lever member 19 is provided with a suitable guide pin 24 which passes through the slotted opening 18 of the inner lever member 13 which when the outer lever member 11 is moved up or down, will raise or lower the outer end of the inner lever member 13 for opening or closing the valve, as is manifest.

The control mechanism for actuating the adjustable valve lever is not shown, excepting the upwardly directed chain thereof, designated 25 and the downwardly directed chain thereof designated 26 for the reason that either a damper regular control mechanism, or a float control mechanism can be employed for actuating the lever and which is not a part of my invention.

From the foregoing description and by reference to the drawings, it will be apparent that sliding the clevis lever member 19 outwardly from the position shown in Fig. 1, and then locking it in such adjusted position by the fastening device 22, will decrease the minimum capacity of the valve when the lever is up and decrease its maximum capacity when the lever is down without in any way affecting the distance of travel of the valve lever member 10 actuated by a control mechanism and by adjusting the clevis lever member 19 in the opposite direction, the minimum capacity of the valve will be increased when the lever member 10 is up and this in turn will increase the maximum capacity of the valve when the lever member 10 is down.

If the clevis lever member 19 is adjusted to the position shown in Fig. 3, with the longitudinal axis at an angle to the longitudinal axis of the outer lever member 10, it will be apparent that when the lever member 10 is up, the valve increases the minimum capacity thereof, whereas when the lever member 10 is down, the valve is open for maximum capacity, thus when clevis member 19 is tilted in the opposite direction to that shown in Fig. 3 and the lever member 10 is up, the valve will decrease the minimum capacity, whereas when the lever member 10 is down, it increases the maximum capacity of the valve.

When the adjustable valve lever is operated by any damper regulator control mechanism, the valve is principally used to control the minimum and maximum speed of a stoker and fan engine, or a turbine and when the valve lever is operated by any float control mechanism, the valve is prin-

cipally used for such purpose as to control the feed water to boilers, or for governing purpose, or controlling water levels, etc.

The many advantages of the herein described invention will readily suggest themselves to those skilled in the art to which it appertains.

I do not wish to be understood as having limited myself to the exact details of construction shown and described, but desire to have it understood that the invention I have shown in the drawings is merely illustrative, as it is manifest that various minor changes may be made in the exact construction and particularly arrangement of parts without departing from the spirit of my invention, hence I reserve the right to make any such changes, or modifications as may fairly fall within the scope of the appended claims when fairly construed.

What I claim is:

1. In combination with a valve casing and a valve stem, a face plate fixed to the valve casing, an outer lever member pivotally connected at its inner end to the face plate, an inner lever member fixed at its inner end to the valve stem and an intermediate lever member connecting the inner lever member with the outer lever member and disposed between said inner and outer lever members.

2. In combination with a valve casing and a valve stem, a face plate fixed to the valve casing, an outer lever member pivotally connected at its inner end to the face plate, an inner lever member fixed at its inner end to the valve stem, an intermediate lever member connecting the inner lever member with the outer lever member and means for longitudinally adjusting the intermediate lever member with relation to the inner and outer lever members.

3. In combination with a valve casing and a valve stem, a face plate fixed to the valve casing, an outer lever member pivotally connected at its inner end to the face plate, an inner lever member fixed at its inner end to the valve stem, an intermediate lever member connecting the inner lever member with the outer lever member, means for longitudinally adjusting the intermediate lever member with relation to the inner and outer lever members and means for adjusting the longitudinal axis of the outer lever member at an angle to the longitudinal axis of the intermediate clevis lever member.

4. In combination with a turning chronometer valve, a face plate fixed to the casing of the valve, a lever consisting of three lever members, one of which members is pivotally connected to the face plate, a second member being fixed to the valve stem of the valve and provided with a slotted opening, and the third member being adjustably supported by the first mentioned lever member and having a sliding pin connection

with the slotted opening of the second lever member.

5. In combination with a chronometer valve having a turning valve stem, a face plate fixed to the casing of the valve, an outer member having a slotted opening pivotally connected to the face plate, an inner lever member having a slotted opening and with a split inner end fixed to the valve stem, 10 an intermediate clevis lever member having a longitudinally disposed slotted opening pivotally supported intermediate its ends by the outer lever member, said intermediate clevis lever member having a transversely 15 disposed curved slotted opening near its outer end, a fastening device passing through the slotted opening of the outer lever member and the curved slotted opening of the intermediate clevis lever member for retaining 20 the latter lever member in various adjusted positions with relation to the outer lever member, a guide pin carried by the inner end of the clevis lever member receivable for sliding movement in the slotted 25 opening of the inner lever member and actuating the inner lever member when the outer lever member is actuated and an adjustable

stop screw carried by the face plate to limit the turning movement of the lever.

6. In combination with a chronometer 30 valve having a turning valve stem, a face plate fixed to the casing of the valve, an outer lever member pivotally connected to the face plate, an inner lever member fixed to the valve stem, an intermediate lever 35 member, means to permit longitudinal adjustment of the intermediate lever member with relation to the outer and inner lever members and means to permit angular adjustment of the intermediate lever member 40 with relation to the inner and outer lever members to control the minimum and maximum capacities of the valve.

7. In combination with a chronometer valve having a turning valve stem, a face 45 plate fixed to the casing of the valve, a lever having pivotal connection with the face plate and fixed connection with the valve stem and said lever having an adjustable member for controlling the degree of turning movements of the valve stem.

In testimony whereof I have hereunto affixed my signature.

WILLIAM KEMP.
